UNITED STATES PATENT OFFICE.

FRANK E. SUMMERS, OF MEMPHIS, MISSOURI.

FLYING-MACHINE.

1,114,201.

Specification of Letters Patent. Patented Oct. 20, 1914.

Application filed October 27, 1913. Serial No. 797,643.

To all whom it may concern:

Be it known that I, FRANK E. SUMMERS, citizen of the United States, residing at Memphis, in the county of Scotland and State of Missouri, have invented certain new and useful Improvements in Flying-Machines, of which the following is a specification.

My invention relates to flying machines, and particularly to mechanism for altering the extent of the plane supporting surface of the machine.

The primary object of my invention is to provide a glider having in combination with relatively fixed and rigid planes, plane sections which are shiftable at the will of the aviator.

A further object of the invention is to provide in connection with a flying machine movable planes having certain sections thereof pivoted so that when the plane moves downward the sections will close so as to press upon the air beneath.

A further object of the invention is the provision in connection with a flying machine of a vertically movable plane having certain sections thereof pivotally mounted so that when the plane is moved downward the sections will exert a pressure upon the air immediately behind the sections so as to assist in forcing the flying machine forward.

A further object of the invention is the provision in connection with a flying machine of fixed planes disposed toward the forward end and rear end of the machine, and opposed intermediate planes which are hingedly mounted so that the planes may be reciprocated vertically, these movable planes being constructed of a series of hinged or pivoted sections so formed as not to impede the upward movement of the hinged planes but to exert a pressure on the air upon a downward movement of the planes.

A further object of the invention is the provision in a flying machine of a gas field, a frame heavier than air partially supported by said field, and movable planes so constructed as to exert when operated either a downward pressure against the air to cause the machine to lift, or a rearward pressure to cause the machine to move forward.

A further object of the invention is to provide a flying machine particularly adapted to be propelled and raised from the ground through manual actuation by the aviator, in which nearly all of the dead

weight of the machine is supported by means of the gas field so that any downward pressure upon the air exercised by the aviator in operating the machine will cause the machine to rise.

A further object of the invention is the provision in connection with a machine of the type above referred to, of wings or planes so constructed that a vertical reciprocation or oscillation of the wings or planes will cause the machine to rise or prevent it from falling and will coincidentally urge the machine forward.

My invention is illustrated in the accompanying drawings wherein:

Figure 1 is a perspective view of a flying machine constructed in accordance with my invention. Fig. 2 is an under side plan view thereof, the gas field however being removed. Fig. 3 is a transverse section of the machine, the front fixed plane being removed. Figs. 4 and 4^a are diagrammatic views showing the operation of the lifting sections on the movable wings or planes. Figs. 5 and 5^a are diagrammatic views illustrating the operation of the propelling sections on the lifting wings or planes. Fig. 6 is a fragmentary detail view of one of the wings.

Corresponding and like parts are referred to in the following description and indicated in all the views of the accompanying drawings by the same reference characters.

Referring to the drawings, 2 designates a gas field of any suitable construction but illustrated as having the ordinary cigar shape. Swung from this gas field in any suitable manner is a framework 3 of any suitable construction designed to support the aviator, the front and rear planes and the movable planes.

Disposed at the forward end of the framework 3 is a fixed plane 4 which extends transversely of the machine and is constructed in the usual manner of longitudinally extending ribs 5 covered with canvas or other suitable material 6. The rear plane 7 is constructed in precisely the same manner as the plane 4 but is disposed at the extreme rear end of the frame 3.

The front and rear planes are spaced from each other as illustrated clearly in Figs. 1 and 2, and disposed in this space and freely movable therein are the wings or planes designated generally 8. Both of these wings or planes are constructed in the same man-

ner and therefore a description of one wing or plane will equally apply to the other.

Each of the wings or planes 8 comprises a basal portion 9, which is relatively rigid and extends longitudinally of the machine. The next section 10 of each wing or plane comprises a series of slats, valves or pivoted sections, each of these slats or valves being designated 11. These slats or valves extend transversely of the length of the machine.

The tip of each wing or plane is composed of a plurality of slats designated 12, each slat or section being pivotally mounted upon the frame 13 which forms the framework of the wing. The flaps or valves 11 are pivotally mounted upon the parallel longitudinally extending frame members 14 by pintle rods 15 which extend between the frame members 14. Each of the slats or sections 11 has a width greater than the distance between the pintle rods 15 so that when the wings close as illustrated in Fig. 4^a, a practically rigid plane surface will be provided resisting any downward movement of the wing. The slats or valves 11 however upon an upward movement of the wing will take a vertical position as illustrated in Fig. 4 and the edges of one valve 11 are connected to the frame of the wing rearward of the pintle rod of the next rearward valve 11 by means of cords 16. The purpose of these hinged or pivoted sections or slats 11 is to permit the easy upward movement of the hinged wing, in other words, to "feather" as the wing or plane moves upward, but to close as the wing or plane moves downward, thus pressing against the air beneath and assisting in the elevation of the machine.

The slats or sections 12 are also pivoted each upon a pintle rod 17 but these slats are so formed that they will pass between the pintle rods so as to take the position shown in Fig. 5 upon an upward movement of the wing and the position shown in Fig. 5^a upon a downward movement of the wing, these slats being held from further movement in either direction by means of the cords 17^a attached to the pintle rod in advance. It will therefore be seen that upon an upward movement of the wing, these slats or sections 12, will act rearwardly against the air behind the machine or behind the slats, thus forcing the machine forward, and that upon a downward movement of the wing the same action will occur so that a reciprocation of the wings 8 will cause not only a lifting force to be exerted upon the machine but will cause the machine to be propelled forward. It will be understood that the wing frames 13 are to be pivoted to the main frame in any suitable manner and that I do not wish to limit myself to any particular construction for these wing frames or planes.

Preferably the weight of the wings 8 is counterbalanced by means of one or more

springs 18 connected to bell cranks 19 which are connected by cords 19 to the tips of the wings. These will normally hold the wing frames upwardly and outwardly inclined in the position shown in Fig. 3. The wings are operated by means of longitudinally extending bars 20 which the operator grasps, these bars being connected by means of rods 21 to the wing frames. The operator is supported upon the main frame 3 of the machine in any suitable manner and as illustrated is supported upon a seat mounted in the lower portion of the main frame so that the legs of the operator will depend below the frame of the machine. This is to permit the operator to alight easily upon the ground or to run a short distance, as for instance from an eminence and glide off into the air. The machine is guided vertically in any suitable manner but I have illustrated for this purpose a rudder 22 which is cruciform in section. This rudder is hinged for movement in a vertical plane and may be operated in any suitable manner by the aviator, as for instance by connecting the rudder with cords 25, in turn having rings through which the feet of the aviator pass. The wings are braced preferably by a system of cross braces or tension rods 23 and suitable struts 24.

This machine is designed primarily for use as a glider and the wings are to be oscillated vertically like the wings of a bird. After the proper speed has been gained by the action of the wings 12 on the air, as previously described, the wings are intended to be held still in a horizontal position and the machine will glide forward until the speed has so decreased as to make it necessary to rise again and be forced upward by the action of the wings.

The object of the small planes 9 to the bases of the wings 10 is to provide additional supporting surfaces. This solid surface 9 is relatively short and will not offer much resistance to working the wings.

The machine can be started from the top of a fast moving vehicle, or the aviator can run down hill and start against the wind or run with a strong wind and start with it, or can spring from an elevated place. Inasmuch as the machine is counterbalanced by means of the gas field 2, there will be no danger of falling precipitately. After the machine is started, the operator oscillates the wings 8, and this action will exert sufficient lifting force to raise the machine and at the same time will exert a propulsive force.

To turn a circle toward the left, the left wing is held still and the right wing is oscillated relatively rapidly and this will cause the machine to turn to the left while by holding the right wing stationary and oscillating the left wing the machine will turn to the right. It is not necessary to move the

rudder in order to steer the machine either to the right or left.

It will be noted that there are two rings 26 connected to the cords 25 through which 5 rings the aviator inserts his feet. One of these rings and the corresponding cord acts to draw the rudder downward while the other acts to raise the outer end of the rudder. The lifting force of the gas field 10 will about balance the weight of the machine and when the aviator gets a good start he can raise the rudder and this will tend to turn the front ends of the planes upward. A propeller might also be used for the purpose 15 of forcing the machine forward and this would act to support the machine in the air without the gas bag, provided that the propeller is run at a sufficiently high speed while the oscillation of the wings would 20 tend to raise the machine. To stop the machine the aviator slides back toward the rear of the machine a little and raises the rudder which tips the forward end of the machine upward, thus offering a greater resistance 25 to the air. This slows the machine down and the aviator alights on the ground and runs forward until the machine stops.

What I claim is:

1. In a flying machine, a framework, forward and rear transversely extending fixed planes mounted on the framework, planes or wings hinged to the framework for movement in a vertical plane and disposed between said fixed planes, each of said movable planes including a rigid section forming the inner portion of each movable plane and a plurality of hinged sections opening upon an upward movement of the plane but closing upon a downward movement, and a gas bag operatively connected to the framework to partially support the framework and planes.

2. In a flying machine, oppositely disposed wings hingedly supported for vertical movement, and means for oscillating said wings, each wing being composed of a plurality of hinged sections, certain of the sections opening upon an upward movement of the wing but closing upon a downward movement 50 thereof, certain other sections being hinged

at their forward edges and opening partially upon a downward or upward movement of the wing to thereby provide a plurality of angularly disposed surfaces acting to propel the machine.

55

3. A flying machine including a framework, a gas field supporting said framework, and oppositely disposed wings each pivoted at its inner end to the framework and oscillatable in a vertical plane, portions of 60 said wings opening downward upon an upward movement of the wing but closing upon a downward movement of the wing to provide a supporting surface, certain other portions of each wing opening partially 65 upon a downward or upward movement of the wing to provide a plurality of rearwardly extending angularly disposed surfaces acting to propel the machine.

70

4. A flying machine including a longitudinally extending frame work, a gas field supporting said frame work, forward and rear transversely extending planes mounted upon said frame work and spaced from each other and oppositely disposed wing frames, 75 each frame being pivoted at its inner end to the frame work and being oscillatable in a vertical plane, the inner portion of each of said wings comprising a relatively rigid section, certain other portions of each wing 80 opening upon an upward movement of the wing and closing upon a downward movement thereof, certain other portions of each wing opening partially upon either a downward or upward movement of the wing to provide 85 a plurality of rearwardly extending angularly disposed surfaces for propelling purposes, a support for the aviator disposed between the oscillatable wings, resilient means urging said oscillatable wings upward, 90 means connected to the frame work of said wings, whereby the aviator may draw them downward and steering mechanism operable by said aviator.

In testimony whereof I affix my signature 95 in presence of two witnesses.
